F. L. BAER

INTEROFFICE TRUNK CIRCUITS FOR TELEPHONE SYSTEMS

Filed June 18, 1920

UNITED STATES PATENT OFFICE.

FRED L. BAER, OF BERWYN, ILLINOIS, ASSIGNOR TO AUTOMATIC ELECTRIC COMPANY, OF CHICAGO, ILLINOIS, A CORPORATION OF ILLINOIS.

INTEROFFICE TRUNK CIRCUITS FOR TELEPHONE SYSTEMS.

Application filed June 18, 1920. Serial No. 389,818.

To all whom it may concern:

Be it known that I, FRED L. BAER, a citizen of the United States of America, and a resident of Berwyn, Cook County, and 5 State of Illinois, have invented certain new and useful Improvements in Interoffice Trunk Circuits for Telephone Systems, of which the following is a specification.

My invention relates in general to inter- 10 office trunk circuits for telephone systems, but more especially to trunk circuits for connecting automatic offices with manual offices in the same system; and the object of the invention is the provision of an improved 15 automatic to manual trunk circuit which is particularly useful for temporarily connecting automatic and manual offices during a cut over, although if desired the trunk circuit may be used in permanently connect- 20 ing such offices where automatic and manual systems serving the same territory are consolidated.

When a manual system is changed or cut over to an automatic system, the usual practice is to cut over one office at a time and it necessarily follows that during the period of change, which may last for several years, both automatic and manual offices will be in operation. This renders it necessary to 30 provide suitable trunk circuits for interconnecting the two different types of central offices, that is, automatic to manual trunks and manual to automatic trunks must be provided to handle the interoffice traffic. 35 This invention is concerned with the former class of trunks and may be considered as an improvement over former trunk circuits in that special means is provided for cancelling or absorbing certain digits in the telephone numbers of subscribers who are for the time being connected to a manual office which will ultimately be changed over to an automatic office.

This special means is a switching device 45 which I term a digit absorber, the operation and special function of which will be described fully hereinafter, reference being had to the accompanying drawing, which is a circuit diagram of an interoffice trunk circuit embodying the principles of the invention.

Referring to the drawing, the reference characters 30 and 31 indicate the two conductors of an interoffice trunk line. This

trunk line extends from the so called digit 55 absorber E, which is located in an automatic office, to an answering jack J at an A operator's position in a manual office and is one of a group of similar trunk lines which are provided to handle the traffic 60 from the automatic office to the manual office. In order to give the automatic subscribers access to these trunk lines, they may be multiplied in the banks of selector switches in the automatic office in the usual 65 manner. Thus the trunk line shown in the drawing may be reached by way of bank contacts 2, 3, and 4, which may be located in the bank of a first selector switch, being connected in multiple to similar contacts in the 70 banks of the other first selectors. The automatic switches are of the well known Strowger vertical and rotary type, operated according to the well known two wire system of control, and may be the type disclosed in U. S. Patent No. 1,281,112 granted Oct. 8, 1918 to B. D. Willis, and the digit 75 absorber E, in addition to its digit absorbing function, also functions as a repeater to establish a holding circuit for any 80 selector which is operated to establish connection with the trunk line associated therewith. This provision is in accordance with the usual practice and is made primarily 85 to avoid the necessity of having three conductors between offices.

As stated before, the answering jack J is located at an A operator's position in the manual office. The particular A operator in front of whom this jack appears may handle 90 trunked calls exclusively, or the jacks associated with the incoming trunks from the automatic office may be distributed among a plurality of operators positions. In any case, the trunked calls are handled substantially like local calls originating in the manual office and the operator, or operators, have uniform supervision. Cord circuits of the type illustrated in the fourth edition of "American Telephone Practice," page 100 315, may be used.

The group of relays indicated by the reference character F are the trunk relays, are located at the manual office, and their functions and operations will be described 105 fully in the course of the general explanation. The trunk equipment at the manual office, it may be stated, forms no part of my

invention, but is claimed in the pending application of Willis, S. N. 389,820, filed June 18, 1920.

For the purpose of explaining the operation it will be assumed that a subscriber in the automatic office desires to obtain connection with a subscriber in the manual office, and the process of setting up the connection will be described. When the receiver is removed the calling line is extended by means of an individual line or trunk selecting switch to an idle first selector switch in the usual and well known manner, and the calling subscriber may then operate his calling device in accordance with the desired number.

The manual subscribers will have full and complete telephone numbers listed in the directory, in accordance with a comprehensive numbering system which has been previously worked out, and these telephone numbers are the numbers which will be used after the service is changed over completely to automatic. For the present the first digit is the only one which has to do with the control of an automatic switch, the remaining digits in any particular number being the ones which correspond to the location of the associated line in the multiple at the manual office.

When the calling dial is operated for the first digit in the number the first selector is directly controlled to raise its shaft step by step until the wipers stand opposite the level which is reserved for the trunks extending to the desired manual office. At the end of the vertical movement of the selector the rotary trunk selecting movement is initiated automatically and the wipers are rotated step by step in search of an idle trunk line. Assuming that the trunk line shown in the drawing is the first idle trunk line, when the wipers arrive at bank contacts 2, 3, and 4 the rotary movement will cease and by the operation of the switching relay in the selector the calling line will be extended by way of the selector line wipers, bank contacts 2 and 4, and conductors 16' and 18 to the upper and lower windings, respectively, of the double wound line relay 5 of the digit absorber E.

Upon the extension of the calling line as above described the line relay 5 is energized over the line circuit and closes a circuit for the slow acting release relay 6 at its armature 9. Upon energizing, relay 6 closes a holding circuit which may be traced from ground G² by way of the left hand winding of induction coil R, normally closed contact springs controlled by armature 13, working contact of armature 10 and the said armature, release trunk conductor 17, test contact 3, test wiper of the operated first selector, and the winding of the switching relay in said selector to battery. This circuit

serves to maintain the selector in operated position during the call and it may be added that a branch of the above circuit performs the same function for the subscriber's individual line switch. It will be understood also that the ground potential on test contact 3 extends to multiple test contacts in the banks of other selector switches thereby rendering the trunk line busy.

The calling subscriber may now operate his calling device in accordance with the next digit of the desired number. As a result the line relay 5 is deenergized a plurality of times and sends a series of impulses to the slow acting relay 8, which attracts its armature and closes a circuit for the stepping magnet 23 of the digit absorber switch mechanism. The magnet is energized and attracts its armature, causing the pawl carried thereby to engage the next notch in the ratchet wheel. Relay 8, being slow acting, remains in operated position throughout the series of impulses, and only retracts its armature when the impulses cease. The circuit of the stepping magnet is then broken, its armature is retracted, and wipers 19 and 20 are advanced into engagement with the first contacts in their respective banks.

The calling subscriber may now operate his calling device in accordance with the remaining digits in the desired number, and each time a digit is called the wipers 19 and 20 will be advanced one more step by the magnet 23. Assuming that the complete telephone number consists of five digits, upon the calling of the final digit the wipers will be brought into engagement with the fourth contacts in their respective banks, and wiper 19 will close a bridge across trunk conductors 30 and 31 as follows: from trunk conductor 30 by way of the winding of relay 7, armature 15 and its working contact, right hand winding of induction coil R, wiper 19 and bank contact engaged thereby, and conductor 21 to trunk conductor 31. It follows that relay 7 will be energized in series with relays 33 and 34 at the manual office, the latter two relays being bridged across the trunk line in series with the battery. Upon energizing, relay 7 grounds the holding circuit direct at its armature 13 and thus cuts out the left hand winding of the induction coil R. At the manual exchange the relays 33 and 34 jointly close a circuit for the answering or call signal lamp L. At the same time relay 34 connects up a lead from the ringing machine R. M. Condenser 51 is of very low capacity, preferably about .005 M. F., and permits just enough ringing current to leak back through the receiver at the calling station to give the calling subscriber the usual ringing current induction. An audible signal of this kind is customary in automatic systems and is provided here for the sake

5 of uniformity. Hearing the signal, the calling subscriber will understand that the desired line is being signalled and will wait on the line, although, as a matter of fact, the 5 ringing machine has nothing to do with the signalling operation that has actually been performed.

It will be seen that although the inter-office trunk line is connected with on calling 10 the first digit of the number, the answering lamp at the operators position is not lighted at once, but remains unlighted until the digit absorber has been stepped around by the calling of the remaining digits far 15 enough to close the bridge across the trunk line. This eliminates the possibility of the operator attempting to answer the call while the calling subscriber is still engaged in operating his calling device. Conductor 21 20 may be shifted, if necessary, to some other contact in the bank of wiper 19, the contact to which it should be connected depending of course on the numbering scheme in use.

When the operator sees the lighted answering lamp L, she will understand that 25 a call has been received over the associated trunk line and will respond by plugging into the jack J with an idle cord circuit. This lights the supervisory lamp in the cord circuit and energizes the sleeve relay 35. Relay 35, upon energizing, prepares a locking circuit for relay 36 at its armature 44, and at its armatures 43 and 45 disconnects 30 relays 33 and 34 from the trunk line. This causes the answering lamp L to be extinguished, and also disconnects the ringing machine R M. At the same time relay 7 at 35 the digit absorber E deenergizes and connects the left hand winding of repeating coil R into the holding circuit again.

The operator will now throw her listening key and will note whether or not there is a 40 discriminating tone on the line. This operation is necessary of course only in case a charge is made for interoffice calls, which 45 the operator is required to record. Any subscriber whose credit is poor and who is to be denied interoffice service on that account has his individual line switch circuit 50 so arranged that a distinctive audible tone is placed on the holding circuit whenever a call is attempted. This tone is transferred to the line at the digit absorber E by means 55 of the repeating coil R, and when heard by the operator is sufficient authority for her to refuse to complete the connection. Reference is again made at this time to U. S. Patent No. 1,281,112, granted Oct. 8, 1918, 60 to B. D. Willis, which shows and describes in full an arrangement of this kind. In order to proceed with the explanation we will assume that no tone is heard by the operator when she comes in on the line, which means that the calling subscriber is 65 entitled to service. The operator will there-

fore obtain the desired number from the calling subscriber and will proceed to complete the connection with the other end of her cord circuit, either directly or with the assistance of a B operator, depending on 70 the particular type of manual exchange in use. The connection having been established the operator will actuate key K momentarily and need pay no further attention to the call, unless recalled by the supervisory signals in the cord.

When key K is operated a circuit is closed for relay 37 which, upon energizing, closes a circuit for relay 36 at armature 49. Upon energizing, relay 36 locks itself at armature 47 and at armature 46 prepares a circuit for relay 34. In addition to closing the circuit of relay 36, relay 37 connects its upper winding in shunt of condenser 52 by means of its armature 48. Condenser 52 is included in the upper conductor of the trunk line, normally preventing current flow from the cord circuit; and it follows that when the condenser is shunted by the winding of relay 37, the said relay will be locked up 80 by current flow over a circuit which includes the battery at the cord circuit, the supervisory relay at the cord circuit, and the relay 7 at the digit absorber E. Relay 7 is accordingly energized again to cut out 85 the left hand winding of induction coil R, and at the cord circuit the supervisory relay is energized to put out the supervisory lamp. It may be mentioned also that relay 90 7 disconnects the condenser which is normally bridged around its winding for the purpose of giving a good circuit for the distinctive tone, when the tone is on the line.

The complete connection has now been 95 established and when the called subscriber in the manual office answers the conversation can begin.

When the subscribers are through talking 100 they will both replace their receivers. When the called subscriber hangs up the operator is given the usual disconnect supervision at the calling end of the cord circuit. When the calling subscriber hangs up the line relay 5 at the digit absorber E is permanently deenergized and falls back to 105 break the circuit of the slow acting release relay 6. The latter relay then deenergizes also, the holding circuit is broken, and the first selector and individual line switch are 110 released. Relay 6 also closes a circuit for release magnet 22 as follows: from the grounded armature 9 of the line relay by 115 way of the resting contact of said armature, armature 11 and its resting contact, bank 120 contact engaged by wiper 20 and the said wiper, conductor 24, and the winding of release magnet 22 to battery. By the energization of the release magnet the retaining pawl and driving pawl are both withdrawn 125 from the ratchet wheel and the 130

wipers are restored to normal, the circuit of the release magnet being broken by wiper 20 when it is completely restored.

When the digit absorber is released wiper 5 19 opens the bridge across trunk conductors 30 and 31, and as a result relay 7 and the supervisory relay in the answering end of the operator's cord circuit are deenergized. The latter relay permits the answering 10 supervisory lamp to be lighted and the operator now has a disconnect signal at both ends of her cord circuit. At the same time that the supervisory relay falls back the relay 37 deenergizes and thereby disconnects 15 its upper winding from in shunt of condenser 52. Relay 36, however, remains locked up.

The operator may now pull down the connection and if she does so relays 35 and 20 36 will be deenergized and all the apparatus will be in normal position. However, in order to complete the explanation we will assume that another call is received over the same trunk line before the operator has 25 had time to disconnect. Sometimes, especially during rush hours, the operators are rather slow at pulling down connections, and this may well occur. When the second calling subscriber connects with the trunk 30 line the line and release relays 5 and 6 are energized as before, and when the calling of the number is finished the bridge including relay 7 is closed across the trunk line by wiper 19 of the digit absorber. As a 35 result a circuit is closed for relay 34, which is now connected to the upper line conductor by way of armatures 43, 46, and 48, for although relay 33 is disconnected, the lower line conductor goes to battery at the manual exchange, nevertheless, because the cord 40 is still up. The supervisory relay at the cord circuit is included in the lower talking strand, which goes to the ungrounded pole of battery and it follows that relays 45 34 and 7 and the supervisory relay in the cord will be energized in series. This puts out the supervisory lamp and removes one of the disconnect signals. Relay 34 being now operated the circuit of the answering lamp L is closed, but since relay 33 is at normal the lamp circuit will be closed 50 through the interrupter I. This causes the lamp to flash which is more effective in recalling the operator than a permanent signal would be.

On perceiving the flashing line lamp the operator will replug in order to restore the circuits to the usual call received condition. That is, she will withdraw the plug from 55 jack J for an instant in order to deenergize relays 35 and 36. When the plug is reinserted relay 35 will pull up again, but not relay 36; and relay 34, which falls back when the plug is withdrawn, will remain deenergized. The circuits are now in the

same condition as they were in the case previously described, when the trunk line was first taken for use, and the operator will proceed according to the usual routine.

Although it is not essential, I have shown 70 a test jack J' which is provided for the convenience of a switch board man or other employee in testing the trunk circuit. These test jacks may be mounted on the relay racks in the terminal room and afford ready access 75 to the trunk circuits. When the jack J' is connected with, a telephone or other testing device is bridged across the two upper springs of the jack while the two lower springs are short circuited. The latter operation energizes relay 32 which pulls up 80 and opens the two sides of the trunk line, leaving the test telephone bridged across the line in the direction of the operator. The 85 person testing can now talk to the operator and ascertain if the trunk line is working or not. Relay 32 also connects the ungrounded pole of battery to the upper trunk conductor 30. Relay 6 at the digit absorber being at normal, relay 7 is now energized 90 by current flow over the upper trunk conductor and at its armature 12 connects ground to the release trunk conductor 17. This renders the trunk line busy. It will be 95 understood that if the trunk circuit should get out of order so that it would become necessary to establish a permanent busy condition, the lower springs of the test jack can be short circuited by means of any small metallic object which may be left in place 100 until the circuit is repaired.

Having described my invention, what I consider to be new and desire to have protected by Letters Patent will be pointed out 105 in the appended claims.

What I claim is:

1. In a telephone system, means for connecting calling and called lines comprising a trunk line extending to an operator's position, automatic switching mechanism whereby a calling subscriber can connect with said trunk line upon calling less than the total number of digits in a telephone number, and means individual to said trunk line operated responsive to the calling of the remaining digits in the number for signalling the operator.

2. In a telephone system, means for connecting calling and called lines comprising a trunk line extending to an operator's position, automatic switching mechanism whereby a calling subscriber can connect with said trunk line upon calling less than the total number of digits in a telephone number, and a digit absorber individual to said trunk line operated responsive to the calling of the remaining digits in the number for signalling the operator when the calling of the number is completed.

3. In a telephone system, means for con-

necting calling and called lines comprising a trunk line extending to an operator's position, automatic switching mechanism whereby a calling subscriber can connect with said trunk line upon calling less than the total number of digits in a telephone number, a digit absorber operated responsive to the calling of the remaining digits in the number for closing a bridge across said trunk lines, and a signal at the called operator's position actuated when the bridge is closed.

4. In a telephone system, a trunk line connecting automatic and manual exchanges, a visual signal at the manual exchange, means including automatic switches whereby a calling automatic subscriber can connect with said trunk line by calling the first digit in a telephone number, means in said trunk line responsive to each digit of the telephone number, said means closing a bridge at the outgoing end of said trunk line only when the final digit of the telephone number has been called for causing the operation of said signal.

5. In a telephone system, a trunk line connecting automatic and manual exchanges, means including automatic switches whereby a calling automatic subscriber can connect

with said trunk line by calling the first digit 30 in a telephone number, a digit absorber in said trunk line, a motor magnet for said digit absorber, means in said trunk line responsive to each digit for completing a circuit for said motor magnet, a normally 35 open bridge in said trunk line, a signal at the manual exchange operated when said bridge is closed, and means in said absorber for closing said bridge after the final digit has been called.

6. In a telephone system, a trunk line having one end terminating in terminals of an automatic switch at an automatic exchange and the other end terminating in a jack at a manual exchange, an automatic switch in 45 said trunk line, means controlled by a calling subscriber for operating said first switch to seize said trunk line and for them operating said second switch through a plurality of positions, a bridge in said trunk line 50 closed by said last switch only when it has been moved into a particular position, and a signal at the manual exchange operated when said bridge is closed.

Signed by me at Chicago, Cook County, 55 Illinois, this 14th of June, 1920.

FRED L. BAER.
